UNITED STATES PATENT OFFICE.

GEORGE W. YANNEY AND WALTER D. KELLER, OF ALLIANCE, OHIO, ASSIGNORS TO THE ALLIANCE MACHINE COMPANY, OF ALLIANCE, OHIO, A CORPORATION OF OHIO.

TONGS.

Application filed August 11, 1922. Serial No. 581,266.

The present invention relates broadly to improvements in tong constructions and more particularly tongs of the type used for handling ingots, and carrying the same 5 to and from soaking pits and the like, although its use in this respect is not limited.

At the present time it is customary to operatively support tongs of this general character from a bridge crane trolley, the tongs 10 operating motor being carried by the trolley. This makes it necessary to provide a special trolley for all such cranes. Not only is this practice a costly one, but it does not provide a flexible and interchangeable working unit. 15 By the present invention there is provided an improved construction embodying as a unit tongs and a tongs operating motor adapted to be suspended from an ordinary crane hook. This provides a flexible construction by means of which one unit may be 20 used with a plurality of cranes of any desired construction.

In the accompanying drawings there is illustrated a preferred embodiment of the 25 present invention, it being understood that the drawings do not define the limits of this invention, as changes may be made in the construction and operation disclosed herein, without departing from the spirit of the invention or scope of our broader claims.

In the drawings,—

Figure 1 is a side elevation, partly in section, illustrating one embodiment of the present invention;

Figure 2 is a side view of the construction illustrated in Figure 1; and

Figures 3 and 4 are detail sectional views on an enlarged scale.

In accordance with this invention there 40 may be provided a suitable frame 2 carrying at its lower end converging guides 3 adapted to cooperate in well known manner with the upper end of tongs 4. The tongs in turn may be pivotally connected to a cross-head 45 5 operatively secured to a tension rod 6 adapted to be raised and lowered by the sheave block 7.

The frame 2 may be of sectional construction and is preferably enlarged adjacent its 50 upper end to form a casing 8 for a tongs operating motor 9. This motor may conveniently be rigidly supported on a platform 10,

constituting a part of the frame 2, and has its driving pinion 11 meshing with a gear 12 operatively secured adjacent one end of a 55 three-bearing shaft 13 journaled in the frame. Adjacent its opposite end, the shaft 13 carries a gear 14 meshing with diametrically positioned planet gears 15. The gears 15 mesh with the teeth of an internal gear 16 rotatably journaled in the frame 2 concentrically with the shaft 13.

Each of the planet gears 15 is mounted on a stub shaft 17 secured in a hub 18 rotatably mounted on a bearing sleeve 19 surrounding 65 the shaft 13 and within which it is rotatable. This hub has projecting therefrom a lug 20 to which is operatively connected one end of a flexible chain 21. This chain passes freely around a sheave 22 in the sheave block 7, 70 and is dead-ended to the frame as indicated at 23.

The internal gear 16 is normally held against rotation by brake shoes 24 pivotally carried by arms 25, each of which in turn has a pivotal mounting 26 on the frame 2. At their upper ends the arms 25 are urged inwardly by means of compression springs 27 cooperatively associated therewith. The braking action exerted by the shoes 24 may 80 be easily adjusted by adjusting the pressure on the springs 27. These brake shoes are preferably so set that during the normal operation of the parts the internal gear 16 will be held against rotation thereby causing 85 the planet gears 15 to travel around its inner surface and thereby rotate the hub 18.

It is desirable with apparatus of this character to definitely limit the lifting action of the motor with respect to the tongs. For 90 this purpose the hub 18 may conveniently be provided with a stop 28 adapted in its different extreme positions to cooperate with opposite sides of the fixed stop 29 secured to the frame 2. With this construction it 95 will be apparent that the rotation of the hub 18 will be abruptly stopped after it has traveled slightly less than 360° in either direction. Overrunning of the motor, however, is permitted by reason of the brake 100 shoes 24, which allow the internal gear 16 to rotate when the stops are engaged. In this manner injury to the apparatus is prevented.

Adjacent the upper end of the frame 2 there may be provided a lifting pin 30 adapted to be engaged by the hook 31 of a suitable overhead crane. The conductor 32 carrying current to the motor 9 may obviously be extended upwardly to the bridge crane trolley, or the like, where a suitable take-up and play-out mechanism may be provided therefor.

10 With the present construction it will be apparent that the tongs and the operating motor therefor constitute a unit which may conveniently be operatively secured to a crane of any standard construction. After 15 the unit has been operatively suspended in position, the motor 9 will be rotated in the hoisting direction for winding the chain 21 around the hub 18 and opening the tongs. The crane will then be operated to move the 20 tongs over an ingot. The tongs will then be lowered by means of the supporting crane until the tongs cross-head 5 rests on top of the ingot. At this time the motor 9 will be reversed and the hub 18 rotated in the opposite 25 direction through approximately its entire movement to allow slack in the chain. Upon lifting the frame 2, by means of the supporting crane, the tongs will close by their own weight and the weight of the supported 30 ingot.

The advantages of the present invention arise from the provision of a unit structure comprising tongs and an operating motor therefor operatively carried by a single frame and adapted to be suspended from a crane or the like of standard construction.

We claim:

1. In a tong construction, a frame, tongs operatively carried by the frame, and a motor carried by said frame and operatively connected to said tongs to raise and lower the tongs bodily relative to the frame, said operative connection being adapted to normally insure movement of the tongs relative 40 to the frame by rotation of the motor but permit rotation of the motor independently of movement of the tongs after predetermined operation of the motor, substantially as described.

50 2. In a tong construction, a frame, tongs operatively carried by the frame, operating connections between the tongs and the frame and a winding drum on the frame connected to the motor through a planetary gear system including a brake and operative connections between the drum and said tongs, said 55 last mentioned connection being adapted to open and close the tongs, substantially as described.

60 3. In a unit tong construction, a frame, tongs operatively connected to one end of said frame, tongs operating motor adjacent the other end of said frame, a main shaft, a winding drum on said shaft connected to the 65 motor by a planetary gear train sur-

rounding said shaft, and means operatively connecting said drum and said tongs, said gear train normally insuring simultaneous movement of the motor and tongs but permitting movement of the motor independently of the tongs upon predetermined rotation of the motor, substantially as described. 70

4. In a tong construction adapted to be supported from a crane hook, a frame, tongs operatively connected to the frame whereby the tongs are opened and closed when moved bodily relative to the frame, a motor mounted on the frame, a winding drum mounted on the frame connected to the motor, and operative connections between the tongs and drum for raising the tongs relative to the frame for opening the tongs, said connections also being arranged to close the tongs when the frame is raised by the crane hook, substantially as described. 75 80 85

5. In a tong construction, a frame, tongs operatively connected to the frame whereby the tongs are opened and closed when moved relative to the frame, a motor mounted on the frame, a winding drum mounted on the frame connected to the motor, operative connections between the tongs and drum for raising the tongs bodily relative to the frame for opening the tongs, a stop for limiting the movement of the drum in both directions, 90 and slip driving connections between the drum and motor, substantially as described. 95

6. A hoisting device comprising a frame, motor supporting means on the frame, a motor on said supporting means, a tong 100 movably supported in the lower end of the frame and arranged to be raised and lowered bodily relative thereto, operating gears interposed between the motor and the tong for raising and lowering the tong upon 105 operation of the motor, said frame and parts carried thereby being balanced about the longitudinal axis of the frame, whereby the frame will hang in a substantially vertical position when suspended, and means on the 110 frame to which flexible suspending means may be attached, substantially as described. 115

7. A hoisting device comprising a frame, a motor in the upper part of the frame, a tong movably supported in the lower end 115 of the frame and arranged to be raised and lowered bodily relative thereto, gearing in the frame operatively connecting the tong with the motor, said frame and the parts thereon being balanced about the vertical 120 axis of the frame whereby the device will hang in a substantially vertical position when freely suspended, and means for flexibly suspending the frame, substantially as 125 described.

8. A hoisting device comprising a frame, a tong operably carried by the lower end of the frame and arranged to be raised and lowered bodily relative thereto, a tong operating mechanism in the frame including a 130

motor and gearing, and means for flexibly suspending the frame, said frame and the parts carried thereby being balanced to hang in a substantially vertical position when suspended, substantially as described.

9. A hoisting unit comprising a frame, a tong operably carried by the lower end of the frame and arranged to be raised and lowered bodily relatively thereto, a tong operating mechanism within the frame above the tong, said mechanism including a motor and gearing, and means on the frame for attachment with a flexible suspending device, said unit being so balanced as to hang in a substantially vertical position with the tong downward when suspended from a flexible suspending means, substantially as described.
10. A hoisting unit comprising a frame, a tong operably carried by the lower end of the frame and arranged to be bodily raised and lowered relative thereto and having its vertical axis coincident with the vertical axis of the frame, tong operating means in the frame above the tong and including a motor and gearing, hook engaging means on the frame, and a hook co-operating with the engaging means, said hook being in line with the axis of the frame, said frame and the parts carried thereby being balanced to hang vertically from the hook, substantially as described.

11. A hoisting unit comprising a frame having a reversible electric motor therein, a tong operably carried by the lower end of the frame below the motor, means operatively connecting the motor and tongs for bodily raising and lowering the tongs relative to the frame for opening and closing the tongs, said means including a reducing gearing and a winding drum, said frame being balanced to hang in a vertical position when

freely suspended, and suspending means thereon, substantially as described.

12. A unit tong construction comprising a frame, a platform in the upper part of the frame, an electric motor on said frame, a tong slidably carried by the lower end of the frame, means interposed between the motor and tong for operatively connecting them for bodily raising the tongs relative to the frame, said means including a reducing gear and hook engaging means on the frame whereby said unit may be suspended from a single hood, said unit having the parts thereof balanced about its vertical axis whereby it will hang in a vertical position when suspended from a hook engaged in said hook engaging means, substantially as described.

13. The combination with a crane hook of a main frame supported thereby, a second frame slidably mounted on the first frame, tongs connected to both frames and arranged to close when the main frame is moved away from the second frame, and a motor on the main frame for moving the second frame toward the main frame to operate the tongs, substantially as described.

14. The combination with a crane hook of a main frame supported thereby, a second frame slidably mounted on the first frame, tongs slidably connected to the main frame and pivotally connected to both frames and arranged to close when the main frame is moved away from the second frame, and a motor on the main frame for moving the second frame toward the main frame to open the tongs, substantially as described.

In testimony whereof we have hereunto set our hands.

GEORGE W. YANNEY.
WALTER D. KELLER.
